UNITED STATES PATENT OFFICE

FRANK A. TALBOT, OF GREENVILLE, SOUTH CAROLINA, ASSIGNOR OF FORTY-FOUR ONE-HUNDREDTHS TO HENRY H. HARRIS, OF GREENVILLE, SOUTH CAROLINA, AND ELEVEN ONE-HUNDREDTHS TO GRAHAME H. POWELL, OF WASHINGTON, DISTRICT OF COLUMBIA

ADJUSTABLE COMBUSTION CHAMBER CONTROL

Application filed May 11, 1927, Serial No. 190,558. Renewed October 17, 1930.

The essence of the present invention lies in the provision of means to control an adjustable combustion chamber in an internal combustion engine, not only in dependence upon 5 the throttle position, but also in dependence upon the engine load. The principal objects of the invention are to secure uniform operating efficiency of the engine and economy of fuel consumption, and it is particularly applicable to the engines of automotive vehicles.

Assuming that a motor is designed to operate on a certain compression pressure under full load at open throttle, it is obvious that as the throttle is moved to closed position, the 15 combustion space remaining the same, the compression pressure lowers so that full efficiency is not obtained from gases not compressed to a sufficiently high pressure. This is due to the fact that when the throttle is 20 closed, there is great resistance to the inflow of the combustion gases, and hence, only a small amount of gas is admitted. This small amount is not sufficient to fill the cylinder, and the result is a very low compression 25 pressure.

Thus the quantity of combustion gases varies to a considerable extent between open and closed throttle. As the throttle approaches closed position, gases drawn into 30 the combustion chamber becomes more and more rarified, and when the size of the combustion chambers remains constant, the gases are accordingly less and less compressed. Thus, the degree of compression at the 35 moment of explosion digresses more and more from the stage at which the engine was designed to operate. It is the object of my invention to render this compression constant at all speeds and under varying loads, and 40 since the unsatisfactory condition heretofore existing is dependent largely upon the variable vacuum in the intake manifold, I base my remedial structure upon this factor itself.

An embodiment of my invention is illustrated on the accompanying sheet of drawing, of which the single figure represents a cross-section through a cylinder of an internal combustion engine provided with my improved control device.

Referring to the drawing, 1 indicates an

internal combustion engine cylinder, the ordinary cylinder head being removed and replaced by a member 2 provided with a cylindrical aperture 3 co-axial with the cylinder 1. For the rest, member 2 is of the same general design as the ordinary cylinder head so as to fulfill all the collateral functions of the latter. A solid, slideable piston 4 is disposed in opening 3, and is provided with usual packing means such as piston rings 5. The function of piston 4 is that of cylinder head, and it will be hereinafter referred to as such. Posts 6 and 7 are rigidly secured in head 4, diametrically spaced and extending upwardly parallel to the cylinder axis. A yoke 8 connects these posts at their tops and is held in position by means of nuts threaded to the ends of the posts.

A shaft 9 is journalled in suitable bearing blocks 10 and 11 so as to extend above the head 4 within the frame outlined by it, the posts, and the yoke. An eccentric 12 is rigidly secured to shaft 9 and has bearing both on the under surface of yoke 8 and on the top surface of head 4. An arm 13 is likewise rigidly secured to shaft 9 and extends to some extent past the cylinder 1.

Beneath the free end of arm 13 is rigidly secured a cylinder 14 with its axis parallel to that of cylinder 1. A piston 15 is arranged for axial movement within cylinder 14, and is connected with the free end of arm 13 by a connecting rod 16, the latter being pivoted to both of the elements. Tubing 17 is arranged to extend between an aperture in the bottom of cylinder 14 and a tap in the intake manifold 18 between throttle valve 19 and the combustion chamber, and means such as spring 20 are arranged to hold arm 13 in the dotted line position when the engine is inoperative.

Upon starting the engine at low throttle, the comparatively high state of vacuum existing in the intake manifold will immediately pull piston 15 down into the position illustrated against the action of spring 20. As the throttle is opened and the vacuum decreases, spring 20 will progressively lift piston 15 and therewith arm 13. The eccentric 12, of course, follows all movements of arm

13, and since piston head 4 moves in dependence upon the eccentric, the compression space 21 will be varied in dependence upon the movements of piston 15, that is, in direct dependence upon variations of the control chamber constituted by cylinder 14 and piston 15. Thus, with high vacuum existing in the manifold, piston head 4 will be in its lowermost position, as indicated, and will be progressively lifted in direct dependence upon the fall of vacuum as the throttle is opened.

In the above description, a constant load has been assumed. Suppose the load to increase, however, at any throttle position, the 15 vacuum in the manifold will be accordingly decreased in dependence upon the slower motor speed. This being the case, piston 15 will move up imparting the same movement to piston 4. Under these circumstances, a larger 20 charge will be admitted into the combustion space and increased power will result.

The mechanical advantage of the transmission means between piston 15 and piston 4 is so designed that explosion impulses on 25 piston 4 will have no appreciable vibratory effect on piston 15. Auxiliary damping devices may, of course, be provided but piston 15 is itself in effect a dash-pot.

When arm 13 is in its dotted line position 30 with the engine operating there is a relatively small degree of vacuum in chamber 14, the vacuum increasing as the throttle is closed. It will be noted, however, that when arm 13 is in its uppermost position, eccentric 35 12 is in its position of maximum mechanical advantage relative to the cylinder head, this advantage decreasing as the arm moves downwardly. This variable leverage effect is of great importance in securing a substantial 40 equilibrium between the force of the motor explosions and the suction force acting in opposite directions on piston 15. By properly designing the transmitting connections between piston 15 and head 4, the oppositely acting 45 force may be substantially balanced at all engine loads and speeds. Under these conditions spring 20 may be entirely dispensed with since upon an opening movement of throttle 19 the cylinder explosions will over- 50 balance the vacuum acting on piston 15 to move piston head 4 outwardly. On the other hand, when the throttle is moved in a closing 55 direction the vacuum acting on piston 15 will momentarily overcome the force of the cylinder explosions acting on head 4 so that the latter will be moved inwardly. It is obvious that a spring 20 will be necessary only when intake suction continually overbalances mean 60 explosion force, and that the two forces may be balanced for all ranges by properly proportioning the illustrated transmission means.

The above disclosure is, of course, merely intended to be illustrative of the general principles of my invention. I do not intend to

restrict myself to any structure other than that determined in the following claims:

I claim:

1. In an internal combustion engine having a cylinder, a head for said cylinder movable axially relative thereto, a suction intake conduit in connection with said cylinder, and a valve in said conduit, the combination of an expansible chamber device in communication with said conduit intermediate said valve and cylinder, means tending yieldably to hold the movable element of said device outwardly thereof, an eccentric for reciprocating said cylinder head, a lever in rigid connection with said eccentric, and connecting means between said lever and the movable element of said expansible chamber device, whereby movements of said element responsive to the variable state of vacuum in said conduit are transmitted to said cylinder head. 75

2. In an internal combustion engine having an adjustable combustion chamber including and adjustable wall and a suction intake conduit, an element actuated in direct dependence upon the vacuum variations in the intake conduit, and a motion transmitting connection between said wall and element moved by the vacuum actuated element to contract the combustion chamber without the assistance of any other force extrinsic to the engine, said connection having a variable mechanical advantage which is at its maximum at the initiation of the combustion chamber contraction. 90

3. In an internal combustion engine having a cylinder and a combustion chamber therein, a movable member bounding a portion of said combustion chamber and adjustable to contract or expand the latter, a suction intake conduit in connection with said chamber, a device having a chamber in connection with said conduit whereby said device is contracted in dependence upon vacuum increases in the conduit, and a motion transmitting connection between said device and said movable member whereby movements of said device in dependence upon vacuum increases in the conduit are positively imparted to the movable member to contract the combustion chamber without the assistance of any force extrinsic to the engine. 105

4. In an internal combustion engine, a cylinder, a head for said cylinder axially movable relative thereto, a suction intake conduit, means actuated in direct dependence upon the vacuum variations in the intake conduit, and a motion transmitting connection between said vacuum actuated means and said cylinder head whereby movements of said vacuum actuated means in dependence upon vacuum increases in the conduit are positively imparted to the cylinder head to move the latter inwardly of the cylinder without the assistance of any other force extrinsic to the engine. 115

5. In an internal combustion engine having a combustion chamber, a movable member bounding a portion of said combustion chamber and adjustable to contract or expand the latter, a suction intake conduit in connection with the combustion chamber, a device having a chamber in communication with said conduit whereby said device is contracted in dependence upon vacuum increases in the conduit, and a positive mechanical connection between said device and said movable member whereby contracting movements of said device are positively transmitted to said movable member to contract 10 the combustion chamber without the assistance of any other force extrinsic to the engine, said connection having a variable mechanical advantage which is at its maximum at the initiation of the combustion chamber contraction.

6. In an internal combustion engine having a cylinder and a combustion chamber therein, a movable member bounding a portion of said combustion chamber and adjustable to contract or expand the latter, a suction intake conduit in connection with said chamber, a device having a chamber in connection with said conduit whereby said device is contracted in dependence upon vacuum increases in the conduit, means acting to expand said device upon vacuum decreases in the conduit, and positive transmission means between said device and said movable member whereby movements of said device in either direction are communicated to said movable member.

7. In an internal combustion engine, a cylinder, a head for said cylinder axially movable relative thereto, a suction intake conduit in connection with the cylinder, a device having a chamber in connection with said conduit whereby said device is contracted in dependence upon vacuum increases in the conduit, means acting to expand said device upon vacuum decreases in the conduit, and positive transmission means between said device and said head whereby movements of said device in either direction are communicated to said head.

8. In an internal combustion engine having a cylinder and a combustion chamber therein, a movable member bounding a portion of said combustion chamber and adjustable to contract or expand the latter, a suction intake conduit in connection with said chamber, a device having a chamber in connection with said conduit whereby said device is contracted in dependence upon vacuum increases in the conduit, means acting to expand said device upon vacuum decreases in the conduit, and a positive mechanical connection between said device and said movable member whereby movements of said device in either direction are communicated to said movable member.

9. In an internal combustion engine having a cylinder and a combustion chamber therein, a movable member bounding a portion of said combustion chamber and adjustable to contract or expand the latter, a suction intake conduit in connection with said chamber, a device having a chamber in connection with said conduit whereby said device is contracted in dependence upon vacuum increases in the conduit, and a motion transmitting connection between said device and said movable member whereby movements of said device in dependence upon vacuum increases in the conduit are positively imparted to the movable member to contract 70 the combustion chamber without the assistance of any force extrinsic to the engine, said connection having a variable mechanical advantage which is at its maximum at the initiation of the combustion chamber contraction. 75

10. In an internal combustion engine, a cylinder, a head for said cylinder axially movable relative thereto, a suction intake conduit, means actuated in direct dependence upon the vacuum variations in the intake conduit, and a motion transmitting connection between said vacuum actuated means and said cylinder head whereby movements of said vacuum actuated means in dependence upon 90 vacuum increases in the conduit are positively imparted to the cylinder head to move the latter inwardly of the cylinder without the assistance of any other force extrinsic to the engine, said connection having a variable 95 mechanical advantage which is at its maximum at the initiation of the combustion chamber contraction. 100

In testimony whereof I have hereunto set my hand.
